ATTORNEY.

UNITED STATES PATENT OFFICE.

HERBERT J. STRAKER, OF NORTH ATTLEBORO, MASSACHUSETTS, ASSIGNOR
TO THE WEBSTER COMPANY, A CORPORATION OF RHODE ISLAND.

DESIGN FOR A BACK FOR BRUSHES, MIRRORS, OR SIMILAR ARTICLES.

No. 38,814.

Specification for Design.

Patented Sept. 17, 1907.

Application filed July 27, 1907. Serial No. 385,926. Term of patent 3½ years.

To all whom it may concern:

Be it known that I, HERBERT J. STRAKER, a citizen of the United States, residing at North Attleboro, in the county of Bristol and State of Massachusetts, have invented a certain new, original, and ornamental Design for a Back for Brushes, Mirrors, or Similar Articles, of which the following is a specification, reference being had therein to the accompanying drawing.

The figure is a plan view of a back for a brush, mirror, or similar article embodying my new design.

I claim,

The ornamental design for a back for brushes, mirrors, or similar articles, as shown.

HERBERT J. STRAKER.
